To all whom it may concern:

Be it known that I, CLARA W. WERTIN, a citizen of the United States, residing at Duluth, in the county of St. Louis and State of Minnesota, have invented a new, original, and ornamental Design for a Toy Bear, Doll, or Similar Article of Manufacture, of which the following is a specification, reference being had to the accompanying drawings, forming part thereof.

resentation of a clothed bear embodied in a toy although the same may also be embodied in or applied to various other articles of manufacture. The lines of shading of the coat of the toy represent the color of red, the lines of shading of the trousers and belt thereof, represent the color of blue, while the lines of shading of the facial features shown represent the color of black.

I claim:

The ornamental design for a toy bear, doll, or similar article of manufacture, as shown and described.
